UNITED STATES PATENT OFFICE.

SAMUEL E. MORTIMER AND WILLIAM V. CLAMPET, OF DAYTON, OHIO.

COMBINED DRILL AND HOLE CLEANER.

Application filed July 13, 1927. Serial No. 205,361.

This invention relates to new and useful improvements in a combined drill and hole cleaner.

It is the principal object of our invention to provide for drilling rock, brick, cement, concrete and other hard or semi-hard material, a simple compact and efficient drill which cleans the hole as it drills it. It also eliminates the friction caused by dust collections, and drills a straighter and truer hole.

Other important and incidental objects will be brought out in the following specification and particularly set forth in the subjoined claim.

15. In the accompanying drawings illustrating our invention, Figure 1 is a longitudinal sectional view taken through our drill. Figure 2 is a cross-sectional view taken through the drill on the line 2—2 of Figure 1. And Figure 3 is a view looking toward the fluted end of the drill.

In the accompanying drawings illustrating our invention, the numeral 1 designates a barrel which is constructed of case-hardened nickel, steel or other suitable material. The upper end of this barrel is internally threaded to receive a flanged plunger collar 2 constructed of cold rolled steel or other suitable metal.

30 Free to move in the bore 3 of the barrel 1 is a plunger 4 that is formed at its middle portion with an annular shoulder 5. To ease the shock of impact of the shoulder 5 with the collar 2, the latter is protected by a leather washer 6 which is placed in the barrel 1 immediately below it. Formed in the barrel 1 below the washer 6 are air inlet holes 7.

The shoulder 5 on the plunger 4 is normally held against the washer 6 by a coil spring 8 that surrounds the plunger between said shoulder and a tool steel tempered disc 9 mounted at the bottom of the bore 3. This disc also receives the shock of the plunger when its upper end is subjected to a hammer blow.

45 Formed in the disc 9 is an axial air hole 10 which communicates with an air hole 11 that leads downwardly through the solid lower end of the barrel to the tapered seat 12 of a ball valve 13. This seat 12 forms the upper end of a bore 14 in the reduced lower end 15 of the barrel 1.

Firmly secured within the lower end 15 of

the barrel by a set screw 16 is the upper end of a drill 17. Formed on the upper part of this drill is a shock shoulder 18, and extending from the top of the drill through its lower fluted end 19, is an axial air hole 20. Supported upon the top of the drill 17 is a helical spring 21 that engages the ball 13 to hold it on its seat 12 to prevent the back suction of dirt from the hole that is being drilled.

In operation, when it is desired to drill a hole in rock, brick, cement or other hard or semi-hard material, a hammer blow is struck upon the outer end of the plunger 4 to cause the drill point 19 to forcibly engage said material. Under the impact of the blow, the plunger 4 will violently descend in the barrel against the tension of the spring 8, to force the air below it through the hole 11, bore 14 and drill passage 20 into the hole being drilled to blow out of it the dust and dirt that are present, thereby eliminating or reducing friction and insuring a straighter and truer hole.

75 The ball valve 13, which has been forced below its seat by the air pressure created by the descending plunger, will be returned to its seat by the spring 21 upon the elevation of the plunger by the spring 8, to prevent back suction of dust and dirt into the barrel 1.

80 Our drill may be operated by the hand, compressed air, steam or electricity to drill a hole in a hard or semi-hard material and clean the hole while it is being drilled.

85 We do not wish to be limited to the details of construction and arrangement herein shown and described, and any changes or modifications may be made therein within the scope of the subjoined claim.

90 Having described our invention, we claim:

A combined hole drilling and cleaning device comprising a barrel having a closed lower end containing an axial hole and a communicating bore of large diameter, a drill point inserted in said bore and containing a communicating axial hole, a plunger in said barrel, a ball valve in said bore to close the hole in the lower end of the barrel, and a coil spring interposed between the ball and the top of the 95 drill point for the purpose specified.

100 In testimony whereof we have hereunto set our hands this 11th day of July, 1927.

SAMUEL E. MORTIMER
WILLIAM V. CLAMPET.
